[57] CLAIM

The ornamental design for an air fairing, as shown and described.

DESCRIPTION

FIG. 1 is a perspective view of one embodiment of an air fairing showing the present invention;

FIG. 2 is a right side view of the embodiment shown in FIG. 1, the left side view is a mirror image;

FIG. 3 is a front view of the embodiment shown in FIG. 1;

FIG. 4 is a back view of the embodiment shown in FIG. 1;

FIG. 5 is a top view of the embodiment shown in FIG. 1;

FIG. 6 is a bottom view of the embodiment shown in FIG. 1;

FIG. 7 is a perspective view of a second embodiment of an air fairing showing the present invention;

FIG. 8 is a right side view of the embodiment shown in FIG. 7, the left side view is a mirror image;

FIG. 9 is a front view of the embodiment shown in FIG. 7;

FIG. 10 is a back view of the embodiment shown in FIG. 7;

FIG. 11 is a top view of the embodiment shown in FIG. 7; and,

FIG. 12 is a bottom view of the embodiment shown in FIG. 7.

The broken line showing of environmental structure in the drawing is for illustrative purposes only and forms no part of the claimed design.
